DIAMOND WHEEL DRESSING TOOL

Walter S. Gockinga, Scarsdale, N. Y., assignor to
 General Industrial Diamond Co. Inc., New
 York, N. Y., a corporation of New York

Application March 2, 1946, Serial No. 651,472

9 Claims. (Cl. 125—39)

1

This invention relates to a diamond wheel dressing tool.

An object of the invention resides in the provision of such a tool that is constructed to include a means for roughing and dressing a grinding wheel.

A further object of the invention resides in the provision of such a tool that combines means for accomplishing face and radius dressing as well as roughing in a combined structure.

It is a further object of the invention to so construct the tool that it can be selectively converted into a face dresser, radius dresser or rougher without removal from the dressing machine.

A still further object of the invention resides in the provision of means for maintaining the face and radius dressing portion in various angular positions in respect of the shank of the tool and for acting as a roughing tool and a protector of the face and radius dressing diamond.

With these and other objects in view, such as will appear as the description progresses, the invention resides in the combination and arrangement of parts illustrated in the drawing, described in the specification and recited in the claims.

In the drawings:

Figure 1 is an elevational view showing the shank and diamond carrying head;

Figure 2 is an elevational view showing the head positioned at right angles to the shank for side or radius dressing and showing the relation of the diamond impregnated collar to the angularly disposed head;

Figure 3 is a similar view showing the head positioned at a 45° angle to the shank for side or radius dressing and showing the relation of the diamond impregnated collar to the angularly disposed head;

Figure 4 is an elevational view showing the relationship of the parts when the tool is to be used for roughing;

Figure 5 is an elevational view looking at one face of the collar; and

Figure 6 is a similar view looking at the opposite face of the collar.

In the form of the invention illustrated in the several figures of the drawing the tool includes a shank 1 which is, preferably, circular in cross section and which is provided at one of its ends with spaced ears 2 which form a slot 3 therebetween. The shank is also provided with a cut 4 that extends from the slot 3 to facilitate the drawing together of the ears 2 in a manner later to be described.

A head 5 that is also, preferably, of circular cross section and which carries a diamond point 6, is provided with a tongue 7 that is located in the slot 3 between the ears 2 of the shank. A

2

longitudinally extending recess 8 is formed in said tongue 7 and a screw 9 which extends through the ears 2 and is in screw threaded engagement with one passes through said slot 3.

Thus, when the head 5 is aligned with the shank 1 and the shoulder 10 engages the ends of the ears 2, the screw 9 may be tightened to draw the ears together and secure the head in its aligned position. A collar 11 is slidably mounted on the shank 1 and head 5 so that it may be moved to the various positions illustrated in the drawing, and this collar is provided with set screws 12 that are adapted to be adjusted to engage the shank 1 or the head 5 to maintain the collar in its various positions of adjustment.

Thus when the head 5 is swung to the right angular position illustrated in Figure 2 for side or radius dressing the collar 11 may be moved on the shank 1 to engage the head on both sides of the longitudinal axis of the shank and secured in this position by the set screws 12. When thus secured to the shank, the collar will maintain the head in its right angular relationship.

In order that the diamond carrying head may be set at various angles for facing or radius dressing, one face of the collar 11 is provided with a plurality of notches 13 that have faces 14 extending at various angles to the longitudinal axis of the shank and the angularities of these notches are indicated by indices 15 on the adjacent face of the collar 11. These notches are arranged to selectively receive the tongue 7 of the head 5 in such manner that one edge of the tongue contacts the face 14. The angularity of the head 5 is thus determined.

When the head is in any of its angular adjusted positions with the tongue in one of the notches, the collar 11 may be secured to the shank 1 by the set screws 12 and will maintain the adjustment of the head.

In order that the collar 11 may be used to rough the grinding wheel and at the same time protect the diamond on the head 5, the collar is made removable and reversible and the face opposite to that in which the notches 13 are formed is set with diamonds 16.

Thus the collar 11 may be loosened on the shank and removed over the head when the head is in alignment with the shank. It may then be reversed and replaced in the position shown in Figure 4. In this position the diamond impregnated face of the collar will be free for use in roughing and the collar will encompass the end of the head 5 with the diamond on the latter located within the recess of the collar and thus protected.

It will be observed that, when the tool is held in a chuck of the machine with which such a tool is used, the collar may be freely adjusted on or removed from the shank without remov-

ing the tool from the chuck. Thus the head may be adjusted into any of its various dressing positions and the collar may be removed and reversed for roughing without removing the tool from the chuck.

While a particular form of the invention has been disclosed, this is for illustrative purposes and the invention is not to be limited to the particular embodiment disclosed except in so far as limitation is made necessary by the claims.

What is claimed is:

1. In a wheel dressing tool, a shank, a head mounted on said shank and pivotally and slidably adjustable thereon to various positions in which its longitudinal axis will lie in various angular positions in respect of the longitudinal axis of the shank, a cutter carried by one end of said head, and a collar slidably mounted on said shank and constructed and arranged to be moved into engagement with said head to maintain said head in its various adjusted positions.

2. In a diamond wheel dressing tool, a shank, a head pivotally and slidably mounted on said shank for adjustment into various angular positions in respect of said shank, and a collar slidably mounted on said shank and constructed and arranged to engage said head to maintain said head in its various adjusted positions, said collar having a plurality of notches therein having faces arranged radially and at various angles with respect to the longitudinal axis of said shank and said head having a reduced portion constructed and arranged to selectively engage said faces and within said notches.

3. In a diamond wheel dressing tool, a shank, a head pivotally and slidably mounted on said shank and carrying a diamond at its end, a collar slidably and removably mounted on said shank and head and having one face thereof set with diamonds, and means for securing said collar on said shank in position to engage and maintain said head in angular relation to said shank and for securing said collar on said head with the diamond on the end thereof housed within said collar.

4. In a diamond wheel dressing tool, a shank, a head pivotally and slidably mounted on said shank and carrying a diamond at its end, a collar slidably and removably mounted on said shank and head and having one face thereof set with diamonds, and means for securing said collar on said shank in position to engage and maintain said head in angular relation to said shank and for securing said collar on said head with the diamond on the end thereof housed within said collar, said collar having a plurality of notches with faces extending at various angles to the longitudinal axis of said shank and said head having a portion constructed and arranged to selectively engage said faces to extend at various angles to the longitudinal axis of said shank and said securing means being operative to maintain said head in its various angular adjustments.

5. In a diamond wheel dressing tool, a shank, a diamond carrying head pivotally and slidably mounted on said shank to extend in alignment therewith or at right angles thereto with a portion extending from opposite sides of the longitudinal axis of said shank, and a collar slidably mounted on said shank and constructed and arranged to engage said head at opposite sides of the longitudinal axis of said shank to main-

tain said head in its said right angular position.

6. In a diamond wheel dressing tool, a shank having spaced ears forming a longitudinal slot at one end thereof, a diamond carrying head having a tongue extending into said slot, said tongue having a longitudinal recess therein, a screw extending through said ears and through said recess and in screw threaded engagement with one of said ears, whereby said head may be adjusted 10 to various angular positions with relation to said shank, and a collar slidably mounted on said shank and head and constructed and arranged to engage said head to maintain the latter in its said various positions of angular adjustment.

15 7. In a diamond wheel dressing tool, a shank having spaced ears forming a longitudinal slot at one end thereof, a diamond carrying head having a tongue extending into said slot, said tongue having a longitudinal recess therein, a screw extending through said ears and through said recess and in screw threaded engagement with one of said ears, whereby said head may be adjusted to various angular positions with relation to said shank, and a collar slidably 20 mounted on said shank and head and constructed and arranged to engage said head to maintain the latter in its said various positions of angular adjustment, said collar having a plurality of notches having head engaging faces extending at 25 various angles to the longitudinal axis of said shank.

30 8. In a diamond wheel dressing tool, a shank, a head pivoted on said shank and carrying a diamond at one of its ends, said head being constructed and arranged to be adjusted to various angles with respect to said shank, and a collar having one diamond impregnated face and one diamond free face, slidably mounted on said shank and head and means for securing said 35 shank and head and means for securing said collar to said shank in position to maintain its diamond free face in contact with said head when the latter is in angular relation to said shank and for securing said collar to said head with the diamond of the latter located within said 40 collar and with the diamond impregnated face of said collar located beyond the diamond of said head.

45 9. In a wheel dressing tool, a shank, a head mounted on said shank and pivotally and slidably adjustable thereon to various positions in which its longitudinal axis will lie in various angular positions in respect of the longitudinal axis of the shank, a cutter carried by one end of said head, and a collar slidably mounted on said shank and constructed and arranged to be moved into engagement with said head to maintain said head in its various positions, said collar being movable on said shank into such position that it will envelop a portion of said head and said cutter.
